J. S. KEEN

EQUALIZING GEAR FOR LOCOMOTIVES

Filed Oct. 25, 1924

Inventor:
John S. Keen
by his Attorneys.
Wilson & Howard

UNITED STATES PATENT OFFICE.

JOHN S. KEEN, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

EQUALIZING GEAR FOR LOCOMOTIVES.

Application filed October 25, 1924. Serial No. 745,897.

To all whom it may concern:

Be it known that I, JOHN S. KEEN, a citizen of the United States, residing in Philadelphia, Pennsylvania, have invented 5 certain Improvements in Equalizing Gears for Locomotives, of which the following is a specification.

My invention relates to certain improvements in equalizing gears of locomotives. 10 The object of the invention is to reduce the height of the equalizing gear so as to allow clearance for parts above the top of the main frame of the locomotive.

In the accompanying drawings:—Fig. 1 15 is a view of sufficient of a locomotive to illustrate my invention; Fig. 2 is a plan view of the mechanism shown in Fig. 1; Fig. 3 is a transverse sectional view on the line 3—3, Fig. 1; Fig. 4 is a sectional view on the line 4—4, Fig. 1; Fig. 5 is a sectional view on the line 5—5, Fig. 1; and Figs. 6 and 7 are views illustrating modifications of the invention.

The frame 1 of a locomotive has pedestals 25 2 between which is located the journal box 3 for the axle 4, on which are the wheels 5. Mounted on the journal box, or formed integral therewith, is a spring seat 6, which is shaped to receive the central band 8 of 30 each of the two semi-elliptical springs 7. These springs extend parallel with the side frame 1 of the locomotive. One spring is located on the outside of the frame and the other spring is located on the inside of the 35 frame, as shown clearly in Figs. 2 and 3.

It will be noticed, on referring to Figs. 1 and 3, that the springs extend only a short distance above the top of the frame 1 to allow sufficient clearance for overhead 40 parts. One end of each spring is connected by a link 9 to an equalizing lever 10, in the present instance, while the other end of each spring is connected by a link 11 to a cross head 12, which is pivoted, at 13, 45 to a bracket 14 that is secured to the under side of the frame 1, as shown clearly in Figs. 1 and 4.

By pivoting the cross bar in the manner shown, any difference in the flexion of 50 the two springs is equalized by this construction. The particular connection shown

may be varied, depending upon the character of the equalizing gear.

In some instances, instead of the pivoted cross bar, shown in Fig. 4, the link 55 11 may be attached to a transverse pin 15, which is mounted in a bracket 14^a that is secured to the frame 1, as illustrated in Fig. 6.

In Fig. 7, another modification is illustrated in which the bearing 6^a for the springs may be mounted on a curved portion 6^b of the box to equalize the two springs.

By the construction hereinbefore described, it will be seen that the entire equalizing gear is materially reduced in height, consequently, sufficient space is provided for the parts of the locomotive that extend over the frame without reducing the 70 effectiveness of the equalizing mechanism.

I claim:

1. The combination in an equalizing gear for locomotives, of a side frame; a box mounted in the side frame; an axle in the 75 box; two springs, one located on one side of the frame and the other located on the opposite side thereof, both springs resting on the box; and means connecting the springs to the frame.

2. The combination in an equalizing gear for locomotives, of a side frame; a box mounted in the frame; an axle in the box, said box having a spring seat; two springs mounted on the seat of the box, one spring being mounted on one side of the frame and the other spring being mounted on the opposite side thereof; an equalizing lever attached to one end of both springs; and links connecting the opposite ends of the 90 springs with the frame.

3. The combination in an equalizing gear for locomotives, of a side frame; a box located in the frame; an axle mounted in the box, said box having spring seats, one 95 on each side of the frame; semi-elliptical springs resting on the seats, one spring being on one side of the frame and the other spring being on the opposite side thereof, one end of the two springs being 100 connected to a part of the equalizing mechanism; means connecting the other end of

the springs to the frame; and means for equalizing the tension of the two springs.

4. The combination in an equalizing gear for locomotives, of a side frame; a box mounted in the frame; an axle located in the box; said box having two spring seats, one at each side of the frame; two semi-elliptical springs resting on the seats, one

spring being located on one side of the frame and the other spring being located ¹⁰ on the opposite side thereof; an equalizing lever connecting one end of both springs; a bearing on the frame; a cross head pivoted to the bearing; and links connecting the arms of the cross head to the springs.

JOHN S. KEEN.
